UNITED STATES PATENT OFFICE.

PHILIP A. KOEHRING, OF MILWAUKEE, WISCONSIN, ASSIGNOR TO KOEHRING MACHINE COMPANY, OF MILWAUKEE, WISCONSIN.

CONCRETE-MIXER.

1,126,487.

Specification of Letters Patent.

Patented Jan. 26, 1915.

Application filed September 8, 1913. Serial No. 788,730.

To all whom it may concern:

Be it known that I, PHILIP A. KOEHRING, a citizen of the United States, residing at Milwaukee, in the county of Milwaukee and State of Wisconsin, have invented certain new and useful Improvements in Concrete-Mixers, of which the following is a specification.

The object of this invention has been to provide certain improvements in the mixing machine described in my United States Letters Patent No. 899,414, issued September 22, 1908, and wherein is provided a peculiarly mounted trough extending into the drum of the mixer and capable of assuming a position for causing a discharge of the contents of the drum as well as being adjustable to a position wherein it acts in an especially advantageous manner to facilitate the mixing of the materials during the rotation of the drum.

The present invention resides primarily in the operating means controlling the said trough, said means being designed with a view of automatically locking the trough in the different positions into which it may be moved, after the respective position is reached.

The details of the invention and its manner of operation will be fully understood on reference to the appended drawings, in which—

Figure 1 is a sectional view of a concrete mixing drum of the rotatable type, illustrating the invention as applied thereto. Fig. 2 is a front elevation of the same.

The mixing drum A shown in the drawing is adapted to be supported upon suitable rollers and is provided with external gears B adapted to mesh with driving pinions, not shown, whereby rotation of the drum may be effected from any suitable source of power, and regulated by convenient controlling mechanism.

In the container or drum A are provided mixing blades or flights C, a suitable inlet opening D being located at one side of the drum and a discharge opening E at its opposite side.

The mechanism forming the present invention is located adjacent to the discharge opening E. On each of the uprights 1 of a suitable frame situated in spaced relation to the drum A is mounted a bracket member comprising brackets 2, said brackets ex-

tending into the discharge opening E and having a guard 2' partially closing the lower portion of said opening. A trough 3 which tapers toward its lower end is supported by the brackets 2, being pivotally connected at 4 at a point intermediate its ends. By reason of the mounting of the trough 3 on the bracket 2 in the manner stated, the outer end of said trough always projects laterally from the mixing drum at 65 the discharge opening E, while the inner portion of the trough is practically housed within said drum. The lower end of the trough 3 is adapted to enter the upper end of a chute 5 when said trough is in what 70 will be hereinafter termed its discharging position. The chute 5 leads away from the mixing drum in a downwardly inclined manner and is designed to readily convey the materials mixed to a suitable receptacle 75 such as a bucket, wheel-barrow, or the like, during the discharging of the contents of the drum. Said chute 5 is supported upon suitable brackets 6 secured in a substantial manner to the frame 1 before mentioned. 80

The means for operating the trough 3 whereby the same may be moved into either of the positions in which it is shown by full and dotted lines in Fig. 1 comprises essentially a shaft 7 mounted in suitable bearings in the brackets 2 and having projecting therefrom a rigid arm 8. The shaft 7 carries at one end an operating lever or handle 9 whereby the shaft may be rocked, and connecting the outer end of the arm 8 with 90 the lower portion of the trough 3 is a curved link 10.

With the above construction in view it will be apparent that by lifting the lever 9 and rocking the shaft 7 the link 10 will be 95 upraised, thereby elevating the lower end of the trough 3 and moving said trough into the inwardly and downwardly inclined position shown by dotted lines in Fig. 1. With the trough 3 in the position just referred to, said trough performs the function of facilitating the mixing operation taking place in the drum A, since the materials in the drum carried upwardly by the blades or flights C will drop on the trough 100 3 and will be thereby thrown toward the inlet of the drum.

When it is desired to discharge more or less of the contents of the drum, the lever 9 will be moved downwardly to the full line 110

position shown in Fig. 1 until the trough 3 rests at its lower end upon the chute 5, at which time the point of pivotal connection between the arm 8 and the link 10 will be lowered into substantial alinement with the shaft 7 and the pivotal connection between said link 10 and the trough 3, whereby the trough will have become automatically locked in its outwardly and downwardly inclined discharge position, permitting the lever 9 to be released without liability of the weight of the materials in the drum accidentally restoring the trough 3 to its mixing or previous position.

Having thus described the invention, what is claimed as new is:—

In a mixing machine, the combination

with a container having a discharge opening, a trough, a support adjacent to the container, a bracket and guard member comprising brackets secured to said support and formed with a guard partially closing said discharge opening, a pivotal connection between said chute and said bracket and guard member, and operating means to impart pivotal movement to the chute for causing the latter to assume an adjusted position.

In testimony whereof I affix my signature in presence of two witnesses.

PHILIP A. KOEHRING.
